UNITED STATES PATENT OFFICE.

JULIUS G. DEXHEIMER, OF MILWAUKEE, WISCONSIN.

DESIGN FOR A SNAP-HOOK.

SPECIFICATION forming part of Design No. 21,982, dated November 8, 1892.

Application filed July 14, 1892. Serial No. 440,073. Term of patent 7 years.

To all whom it may concern:

Be it known that I, JULIUS G. DEXHEIMER, of Milwaukee, in the county of Milwaukee and State of Wisconsin, have invented a new and useful Improvement in a Design for a Snap-Hook, of which the following is a description, reference being had to the accompanying drawings, which are a part of this specification.

10 Figure 1 of the drawings is a view of the outer side of my design for a snap-hook, and Fig. 2 is an edge elevation.

Like letters of reference indicate like parts in both figures of the drawings.

15 The leading feature of my design consists in a snap-hook of the form and surface configuration shown.

Referring to the drawings, the letter A indicates a hook having a tang or reduced portion *a* extending from the same. At the bend of this hook the metal is made oval both interiorly and exteriorly, whereby a thickened surface is presented.

The letter B indicates a plate, which is

formed or provided with a ridge or bulge *b*, 25 rectangular in form, and designed to produce the effect of a loop forming part of an ordinary buckle. The rear end of the plate projects out beyond this rectangular ridge, producing the appearance of the end of a strap 30 passing through the loop.

A projection C is bent down upon the outer face of the plate in imitation of the tongue of a buckle passing through a strap. The hook portion A represents the remaining part of 35 the strap outside of the buckle, while the depressed portion of plate B within the bordering ridge or bulge *b* represents that part of the strap which is passed through the loop.

I claim—

40 The design for a snap-hook, substantially as herein shown and described.

In testimony whereof I affix my signature in presence of two witnesses.

JULIUS G. DEXHEIMER.
